MACHINE FOR GUMMING WRAPPER-BLANKS FOR BOXES OR PACKAGES.

1,302,874.

Specification of Letters Patent.

Patented May 6, 1919.

Application filed May 14, 1917. Serial No. 168,429.

To all whom it may concern:

Be it known that we, JOHN STOGDELL STOKES and ERNEST G. RIDER, both citizens of the United States, residing, respectively, 5 at Moorestown and Philadelphia, in the counties of Burlington and Philadelphia, and States of New Jersey and Pennsylvania, have invented new and useful Improvements in Machines for Gumming Wrapper-10 Blanks for Boxes or Packages, of which the following is a specification.

Our present invention relates to machines for gumming wrapper blanks for boxes or packages.

15 Among the objects of the invention are:

To provide a novel form of rotary blank-supporting platen by means of which the form is readily placed in position without requiring the use of an adhesive coating on 20 the platen surface.

To provide an improved form.

25 To provide improved methods of eliminating the curl which is normally produced on blanks when the latter have been adhesively coated and during the drying of the adhesive, together with apparatus for carrying the methods into effect.

To these and other ends, the nature of 30 which will be readily understood as the invention is hereinafter disclosed, said invention consists in the improved construction and combination of parts, together with the methods, hereinafter more fully described, 35 illustrated in the accompanying drawings, and more particularly pointed out in the appended claims.

In the accompanying drawings, in which similar reference characters indicate similar parts in each of the views:

40 Figure 1 is a diagrammatic view, partly in section and partly in elevation showing a simple form of adhesive-applying mechanism adapted to coöperate with the platen, together with a simple form of delivery 45 mechanism which may be employed to deliver the blanks to the platen.

Fig. 2 is a view in elevation of the platen.

Figs. 3 and 4 are detail views indicating the manner in which the opposite ends of 50 the form-supporting wire strands are secured.

Fig. 5 is a fragmentary sectional view

indicating the manner in which the wire strands coöperate with the form.

Fig. 6 is a view, partly in end elevation 55 and partly in section, showing a platen and its coöperating parts arranged to eliminate the curl.

Fig. 7 is an elevation of the platen of Fig. 6 with portions broken away. 60

Fig. 8 is a detail sectional view showing the arrangement of the platen.

In devices of this type employing a rotary blank-supporting platen for carrying the wrapper during the adhesive-applying operation, it is the general practice to secure a form to the face of the platen, the form conforming more or less to the shape of the blank, the form being positioned on the platen in such manner as to permit proper 70 delivery of the adhesively-coated blank to the mechanism which transfers the coated blank to proper position in the wrapping mechanism. The use of the form tends to raise the exposed face of the blank above 75 the normal face of the platen, and as the adhesive-applying roll or rolls are generally arranged to contact with such raised face, the arrangement tends to reduce liability of applying adhesive to the portions of the 80 platen face not covered by the blank.

The practice heretofore has generally been to secure the form to the platen by adhesive, but this is objectionable owing to the difficulty of cleaning the adhesive from 85 the platen when the form is removed, thorough cleaning being required in order that the face of the platen beneath the form being applied will be free from any raised 90 portions, since the presence of such raised portions would tend to affect the character of the coating.

In the present invention we have overcome this objectionable feature by removably securing the form in position without 95 the use of adhesive, thus eliminating the tendency to produce raised portions on the face of the platen and at the same time eliminating the loss of time which is required in giving the face of the platen a 100 sufficiently thorough cleaning. This result in the instance shown, which is one embodiment of the invention is obtained by stretching a plurality of wire strands of small

- cross-section over the face of the form, these strands passing more or less into the form so as not to present any material raised portions on the face of the form while at the same time retaining the form in proper contact with the platen or with a blanket mounted on the platen—if the blanket feature is employed. The mechanism for producing this action is of a simple type such as will permit of the quick positioning or removal of the form when a change is desired.
- By this change in manner of securing the form, we are also enabled if desired, to use a blanket of felt or other suitable material as the form or as a textile element beneath the form, since there is no requirement of securing the blanket to the platen by the use of adhesive.
- Another feature of the present invention is the method of treating the blank, while on the platen, for the removal of the curl which generally results during the conditioning of the coating preliminary to the application of the wrapper to the box or package, this conditioning tending to produce a more or less "tacky" form of coating on the blank. Blanks of the cornered type are especially subject to this curling action and since this type of blank is usually employed, the difficulty is one generally present.

This curl can be eliminated to a more or less extent by subjecting that face of the blank opposite to the face on which the adhesive is applied, to the action of moisture which, may, if desired, be in the form of steam, thereby "killing" the curl. In the present invention, this application of moisture or steam being preferably had while the blank is on the platen, thus enabling the remedial agent to be applied before the curl has materially developed and practically anticipating the formation of the curl.

In the drawings, 10 indicates a rotary platen having a wrapper-gripping mechanism of any preferred type, indicated at 11. The adhesive-applying mechanism is indicated at α being of any preferred type, that shown in the drawings including a supply roll 12 adapted to receive its supply from a tank 13, a distributor roll 14, and a plurality of rolls 15 of the type having spaced adhesive-applying faces, the faces of one roller being opposite the spaces between the faces of the other roller so that the wrapper blanks, when drawn over the two adhesive-applying rolls, will have a coating of adhesive applied over substantially the entire area of one face of the blank. Obviously, the gumming mechanism may be of a different type and may, if desired, be of types adapted to provide a striped or spotted effect on the blank.

The blanks are delivered to the platen by any desired mechanism, that shown in the

drawings indicating a type in which the bottom blank from the pile is delivered into a throat by a suction roll 16, the blank being advanced by a pair of rolls 17 into the position to be grasped by the gripping mechanism 11.

These mechanisms, while shown in forms now in commercial use, are intended as simply illustrative, any preferred arrangement for these purposes being contemplated within the spirit of the present invention.

As shown in Fig. 1, the form 18 may be of the usual type, as for instance card-board or other material, or, as shown in Fig. 6, it may be of felt or other suitable material. Or if desired, it may be a combination of the two materials by the use of separate layers.

As shown in the drawings, the means for securing the form in position is by a plurality of wire strands 19, of comparatively small gage, these wires being of suitable length and having their ends preferably formed with eyes 19^a which are adapted to be engaged by the hooks of holding devices, 90 these holding devices being located in spaces formed in the platen so that the ends of the wire strands are located below the peripheral face of the platen.

The holding devices may be of any suitable type and may, if desired, be similar at the opposite ends of the strands; but we prefer to employ structures of the type shown in detail in Figs. 3 and 4, in which the strands are held under spring tension, 100 and at the same time the holding devices are such that the strands may be quickly placed in position or removed from such position. In the arrangement shown, 20 indicates a bar of non-circular cross-section 105 on which are mounted a plurality of collars 21 each carrying a hook 21^a on which the eye of a strand is removably supported. The holding means for the opposite end of a strand is provided by a bar 22, preferably 110 of non-circular cross-section and carrying a plurality of collars 23 having apertured projections 23^a. Each projection 23^a carries a rod 24, said rod extending through the aperture of projection 23^a and having one end 115 hook-shaped, as at 24^a, the other end of the rod carrying an abutment 24^b between which and the projection is mounted a coil spring 25, the hook 24^a receiving the eye of the strand.

As will be obvious, the spring 25, when the strand has its opposite ends connected to hooks 21^a and 24^a, will be held under the tension provided by spring 25, the tension of the spring being preferably such as to cause that portion of the strand extending over the face of the form to become more or less embedded in the form as indicated more particularly in Figs. 5 and 8. When it is desired to remove the form, it is necessary 130

only to push rod 24 inwardly, thus relieving the tension on the strand, permitting the eye to be disengaged from either hook. By reversing this operation the strand may be 5 placed in position.

Collars 21 and 23 are preferably slidably mounted on rods 20 and 22, so that the positions of the strands may be varied as desired, and since the direction of pull on the 10 strand remains constant, there is no tendency of the collars to shift when the strands are in position. Obviously, any desired number of strands may be employed, rods 20 and 22 carrying a sufficient number of collars to 15 permit the desired number of strands to be used, it being understood that all or only a portion of the holding devices may be employed at any one time, the active hook devices being those which hold a strand in 20 position.

Owing to the taut condition of the strands and the particular manner in which they are led about the active face of the platen, the 25 form will be held against shifting movements during operation, while at the same time the strands will not materially affect the adhesive-applying operation, due to the fact that the strands are practically embedded within the form and present no material faces projecting above the face of the 30 form. By this arrangement, the form may be formed of any desired material and may, as heretofore pointed out be of paper, paper-board, card-board, etc., or may be of textile material such for instance as felt or 35 canvas.

Mechanism for killing the curl of the blank is shown more particularly in Figs. 6 to 8, embodying structural elements by 40 means of which a moistening or a steaming effect is produced on the blank while the latter is present on the platen. While we have shown a general embodiment of such means, it will be readily understood that 45 other ways for producing the desired result may be employed, and we desire it to be understood that the invention is not limited by the specific mechanism disclosed.

As heretofore pointed out, the curl may 50 be killed either by the application of moisture to that face of the blank opposite to that on which the adhesive is applied, or by the application of steam to such blank face, depending somewhat upon the character 55 of the blank and of the adhesive. In the drawings, the embodiment shown is of a form by means of which either can be employed, but it is to be understood, of course, that the invention is not to be limited 60 to the presence of apparatus for providing a selective action, the invention contemplating the use of moisture-applying means alone. And while the moisture-applying means, in the embodiment shown, forms a 65 part of the steam-producing structure, it is

to be understood that the invention is not limited in this respect, other ways of producing the steam action being considered as falling within the scope of the invention.

In the embodiment shown, the form is 70 preferably, although not necessarily, of the textile fabric type, thus producing a more or less absorbent blank-supporting face on which the liquid, preferably water, can be applied. This action is had by the use of a 75 roll 33 having a suitable surface 33^a which is adapted to contact with the face of the form and also with a suitable supply means 34 extending into tank 35, supply means 34 feeding the water to face 33^a in desired 80 amounts, face 33^a acting somewhat as a distributing face in delivering the water supply to the exposed face of form 18, the amount supplied obviously being small but sufficient to produce a moistening effect on 85 the blank when the latter is in position on the dampened face of the form. Obviously, face 33 may be arranged to provide the water application at predetermined points 90 where the adhesive is applied only at intervals, the particular form shown being adapted to apply the water throughout the face of the form on the assumption that the blank is to be coated throughout its face.

Roll 33 is positioned to contact with the 95 face of the form in advance of the positioning of the blank on the form, so that the form face is dampened when the blank is received by the platen, Fig. 1 indicating one 100 position in which the roll may be located to produce this effect. Hence, when the blank is advanced through the adhesive-applying mechanism, its opposite face is being subjected to the moistening action of the dampened form, the result being that the particular 105 conditions which are conducive to the production of the curl are practically eliminated.

In the instance shown in the drawings, this water distribution on the face of the 110 form provides the water supply for the development of steam, the small amount of water which is applied to form 18 being subjected to the action of heat to generate the water into steam, thus subjecting the under face of the blank to the action of steam rather than the action of moisture. This result is provided by forming the platen, beneath the form, with a space in which is mounted a plurality of electric conductors, 115 indicated as in the form of wires 30 extending in the direction of length of the platen and suitably insulated to produce an electric heating structure, the current being supplied in any suitable manner as by the 120 use of contacts 31 at one end of the platen, and brushes 32 coöperating with the contacts during the travel of the platen, the brushes being connected to a suitable source 125 of electric supply.

The heating device will obviously be of a form which will provide the steam generation with sufficient rapidity to produce a sufficient steam effect while the blank is on 5 the platen to provide the desired curl killing action.

As will be understood, the arrangement of parts will be such as to bring about steam activity as the blank is being received by 10 the platen or at any point subsequent to the positioning of the blank by controlling the amount of water supplied and the amount of heat, it being possible to maintain the heating effect in advance of the positioning 15 of the blank and throughout the travel of the blank in position on the platen, so that assurance is practically had that such steaming action will be presented while the blank is so positioned and prior to the its release 20 from the platen.

As will be readily understood, the presence of the heating means on the face of the platen beneath the form practically prevents the use of an adhesive as the means for 25 securing the form in position, so that it is practically essential that a different type of form-securing means—such for instance as disclosed herein—be employed where the moisture or steam-applying mechanism is 30 employed.

While the form-securing and moisture or steam-applying structures are particularly applicable for use in connection with gumming mechanism for wrappers or other types 35 of blanks, it will be readily understood that these form-securing or moisture or steam-applying mechanisms may be employed in mechanisms adapted for other uses and the invention is therefore not considered as limited 40 in this respect. Similarly, the mechanisms may be employed in conjunction or separately, as the particular uses to which the mechanisms are to be put may require, it not being desired to limit the invention to the 45 conjoint use, since, as pointed out, either may be omitted, depending on the particular use.

While we have herein shown and described preferred ways in which the invention may be carried into effect, it will be readily understood 50 that changes or modifications therein may be found desirable or necessary to meet the exigencies of use, and we desire to be understood as reserving the right to make any and all such changes therein as 55 may be found desirable or essential, in so far as the same may fall within the spirit and scope of the invention as expressed in the accompanying claims when broadly construed.

60 Having thus described our invention, what we claim as new, is:—

1. In combination, a rotary platen having blank-gripping mechanism, a blank support detachably mounted on the platen, and 65 means for securing the support in position,

said means including a plurality of strands overlying the exposed surface of the support.

2. In combination, a rotary platen having blank-gripping mechanism, a blank support 70 detachably mounted on the platen, and means for securing the support in position, said means including a plurality of wire strands overlying the exposed surface of the support. 75

3. In combination, a rotary platen having blank-gripping mechanism, a blank support detachably mounted on the platen, and means for securing the support in position, said means including a plurality of taut 80 wire strands overlying the exposed surface of the support.

4. In combination, a rotary platen having blank-gripping mechanism, a blank support detachably mounted on the platen, and 85 means for securing the support in position, said means including a plurality of strands overlying the exposed surface and more or less embedded within the body of the support. 90

5. In combination, a rotary platen having blank-gripping mechanism, a blank support detachably mounted on the platen, and means for securing the support in position, said means including a plurality of strands 95 overlying the exposed surface of the support, and means for detachably securing said strands in position.

6. In combination, a rotary platen having blank-gripping mechanism, a blank support 100 detachably mounted on the platen, and means for securing the support in position, said means including a plurality of hook members positioned beyond opposite ends of the support, and a plurality of wire strands 105 each having its opposite ends detachably engaging hook members.

7. In combination, a rotary platen having blank-gripping mechanism, a blank support 110 detachably mounted on the platen, and means for securing the support in position, said means including a plurality of hook members positioned beyond opposite ends of the support, bars or rods of non-circular 115 cross-section for supporting the hook members to permit adjustment of the latter in the direction of length of the bars or rods, and a plurality of wire strands overlying the blank support and having their opposite ends detachably secured to hook members. 120

8. In combination, a rotary platen having blank-gripping mechanism, a blank support detachably mounted on the platen, and means for securing the support in position, said means including a plurality of hook 125 members positioned beyond opposite ends of the support, bars or rods of non-circular cross-section for supporting the hook members to permit adjustment of the latter in the direction of length of the bars or rods, a plu- 130

5 rality of wire strands overlying the blank support and having their opposite ends detachably secured to hook members, and means whereby each strand will be held tensioned.

9. In combination, a rotary platen having blank-gripping mechanism, a blank support detachably mounted on the platen, and means for securing the support in position, 10 said means including a plurality of hook members positioned beyond opposite ends of the support, bars or rods of non-circular cross-section for supporting the hook members to permit adjustment of the latter in the 15 direction of length of the bars or rods, and a plurality of wire strands overlying the blank support and having their opposite ends detachably secured to hook members, predetermined hook members carrying tension-applying means for tensioning and yieldably 20 supporting the strands.

10. In combination, a rotary platen having blank-gripping mechanism, a blank support detachably mounted on the platen and comprising a form on which the blank is 25 supported while on the platen, and means for securing the support in position, said means including a plurality of wire strands overlying the exposed surface of the support.

11. In combination, a rotary platen having blank-gripping mechanism, a blank support detachably mounted on the platen and comprising a composite form on which the 30 blank is supported while on the platen, and means for securing the support in position, said means including a plurality of wire strands overlying the exposed surface of the support.

12. In combination, a rotary platen having blank-gripping mechanism, a blank support detachably mounted on the platen and comprising a blanket and a form superposed thereon, and means for securing the support 45 in position, said means including a plurality of wire strands overlying the exposed surface of the support.

13. In the art of gumming blanks, the method of eliminating the curl which consists 50 in facially supporting a blank on a moistened surface, and applying adhesive to the opposite face of the blank while it is thus supported and in the moistened condition.

14. In the art of gumming blanks, the method of preventing the natural curling tendency resulting from application of liquid adhesive to a face thereof, which consists 55 in facially supporting a blank to be moistened and gummed, and concurrently applying moisture and adhesive respectively to opposite faces of the supported blank.

15. In the art of gumming blanks, the method of eliminating the curl which consists 60 in positioning the blank on a blank-

advancing support, applying a liquid to the face of the support in advance of blank positioning, applying adhesive to the blank while so supported, and changing the liquid to steam and applying the latter to the blank 70 while the latter is so supported.

16. In mechanism for removing curl from blanks, a rotary platen having a blank-supporting face, and means for producing on said face a steam effect on the blank while 75 the latter is so supported.

17. In mechanism for removing curl from blanks, a rotary platen having a blank-supporting face, and means for rendering said face active to produce a steam effect on the 80 blank while the latter is so supported.

18. In mechanism for removing curl from blanks, a rotary platen having a blank-supporting face, and means effective on said face for producing a steam effect on the 85 blank while the latter is so supported, said means including a liquid-applying structure adapted to contact with said face in advance of blank positioning, and means carried by the platen for causing applied liquid to be 90 changed into steam during travel of the platen.

19. In mechanism for removing curl from blanks, a rotary platen having a blank-supporting face, and means effective on said 95 face for producing a steam effect on the blank while the latter is so supported, said means including a liquid-applying structure adapted to contact with said face in advance of blank positioning, and heating means carried by the platen for changing applied liquid 100 to steam at such face.

20. In mechanism for removing curl from blanks, a rotary platen having a blank-supporting face, and means effective on said 105 face for producing a steam effect on the blank while the latter is so supported, said means including a liquid-applying structure adapted to contact with said face in advance of blank positioning, electrical heating 110 means carried by the platen and operative to cause applied liquid to be changed to steam at such face, and means for connecting said electrical heating means to a source of supply.

21. In combination, a rotary platen, a blank support detachably mounted on the platen and adapted to produce a blank-supporting face raised from the platen, and means overlying said support for removably 115 securing the support in position.

22. In combination, a rotary platen, a blank support detachably mounted on the platen, and mechanism for securing the support in position, said mechanism including a 120 plurality of strands overlying the support, and means carried by the platen and individually coöperating with strand ends for removably securing the strands in position.

23. In combination, a rotary platen, a 125

blank support detachably mounted on the platen, and mechanism for securing the support in position, said mechanism including a plurality of strands overlying the support, and means carried by the platen and individually coöperating with strand ends for removably securing the strands in position, said means including a plurality of members adjustable in the direction of platen axis to 10 permit adjustment of individual strands on said support.

24. In mechanism of the type described, a rotary blank-supporting platen, a form removably secured to the platen and having a 15 blank-supporting face, means for producing a steam action at said face, and adhesive-applying mechanism operative on the blank while so supported.

25. In mechanism of the type described, a 20 rotary platen having a blank-supporting face, adhesive-applying mechanism operative on the blank when so supported during travel of the platen, and means for causing said face to produce a steam effect on the 25 blank while the latter is so supported.

26. In the art of gumming blanks, the 30 method of eliminating the curl which consists in facially supporting a blank on an absorbent surface, applying a liquid to the said surface to moisten the same and render the

blank moist and limp, and at the same time applying a coating of adhesive to the outer face of the moistened blank while so supported.

27. In mechanism of the character described, 35 a rotary blank-supporting and carrying platen having a blank support of absorbent material adapted to support and moisten a blank to prevent curling thereof, means for moistening said absorbent support, and means for applying an adhesive coating to the exposed face of a moistened blank carried by said support.

28. In mechanism of the character described, 40 a rotary blank-supporting and carrying platen having a blank-support of absorbent material adapted to support and moisten a blank to prevent curling thereof when a coating is applied to its exposed face, means for applying a moistening medium to 45 said absorbent support, means for feeding blanks successively to the moistened support, and means for applying an adhesive coating to the exposed face of a moistened blank carried by said support.

In testimony whereof we have hereunto set 50 our hands.

J. STOGDELL STOKES.
ERNEST G. RIDER.
